UNITED STATES PATENT OFFICE.

JUAN EMILIO NOIRIT, OF WALSALL, ENGLAND.

VELOCIPED-E-SADDLE.

SPECIFICATION forming part of Letters Patent No. 593,331, dated November 9, 1897.

Application filed July 28, 1896. Serial No. 600,807. (No model.) Patented in England June 27, 1894, No. 12,460, and in France November 12, 1894, No. 242,816.

To all whom it may concern:

Be it known that I, JUAN EMILIO NOIRIT, a subject of Her Majesty the Queen of Great Britain and Ireland, residing at Walsall, in the county of Stafford, England, have invented 5 certain new and useful Improvements in Velocipede-Saddles, of which the following is a specification.

Patents have been granted in England, No. 12,460, dated June 27, 1894, and in France, No. 242,816, dated November 12, 1894.

This invention consists of the herein-described improvements in and connected with velocipede-saddles, the chief object of my invention being to so construct a velocipede-saddle that its shape can be readily altered and adjusted to suit the rider.

I will describe my invention by referring to the accompanying drawings, on which—

20 Figure 1 is a longitudinal section of a velocipede-saddle constructed according to this invention. Fig. 2 is plan of the same, partly in section. Fig. 3 is a cross-sectional elevation of the same on line X X of Fig. 2. Fig. 25 4 is a cross-sectional elevation on line Y Y, Fig. 2. Fig. 5 is a sectional elevation of a slightly-modified form of my invention. Fig. 6 is a part sectional plan of the same, and Figs. 7 and 8 illustrate a further modification 30 of my invention. Figs. 9 and 10 show a further modification. Fig. 11 is a sectional elevation, and Fig. 12 is a plan, of a further modification. Fig. 13 is a cross-section on line Z Z of Fig. 12; and Figs. 14 and 15 show 35 parts of the saddle shown in Figs. 11, 12, and 13 separately.

The same letters of reference indicate the same or corresponding parts in all the figures of the drawings.

40 In carrying out my invention, instead of blocking the leather top part of the saddle in one piece, as is usual, I make the said leather part in two separate pieces, (marked, respectively, A' A²)—that is to say, the saddle-top has the appearance of being divided centrally 45 longitudinally from front to back, leaving a narrow space along the center, each of the two portions A' A² of the leather covering being by preference blocked separately to the 50 required shape. These two portions A' A² of

the leather covering of the saddle are, as hereinafter described, so arranged that they can be moved and fixed nearer together or farther apart, so as to alter the width of the saddle either at the front or back or at both the front 55 and back to suit different riders. This fixing of the two portions A' A² of the leather top part of the saddle to the under frame so that they can be adjusted nearer together or farther apart, as stated above, may be effected 60 in various ways. For instance, the two portions A' A² of the leather top part of the saddle may, as shown in Figs. 1, 2, 3, and 4, each be fixed by rivets b at the back of the saddle to a separate metallic runner or slide, which 65 runners or slides are marked, respectively, C' C² and are arranged to fit on and be guided along and engage with the curved back bar D of the metallic under frame, to which the ends of the spring part E are bolted by the 70 bolts f' f², each of these runners or slides C' C² being provided with a clamping bolt or screw g, by which the runners C' C² and the two portions A' A² of the leather top part can be fixed nearer together or farther apart, as 75 may be desired. The bolts g pass through slots in the back bar.

The front end of each of the two portions A' A² of the leather covering part has or may have fixed to it underneath a small metal 80 socket, which two sockets are marked, respectively, H' H², and are or may be connected together by a right and left hand screw I, passing horizontally through them—that is to say, the portion i' of the screw I which passes 85 through the bracket H', fixed to the portion A' of the leather covering, is made with a right-hand thread, and the portion i² of the screw I which passes through the bracket H², fixed to the other portion A² of the leather cov- 90 ering part, is made with a left-hand thread—so that by turning the screw I in one direction the two front ends of the two portions of the leather covering part are brought nearer together and by turning the screw I in the opposite direction they are moved farther apart. 95

The spring E of the saddle may be of any usual kind made with two limbs, the outer ends of which are connected by the bolts f' f² to the curved back bar D, the front of the 100

spring being made, as usual, into a loop e' , with which the hooked end of the usual tension-screw J engages, this screw being tapped into the cross-screw I , so that by screwing the screw J farther in or out of the cross-screw I the tension of the leather parts $A' A^2$ can be increased or diminished, as required.

From the foregoing it will be seen that the width of the saddle either at the front or back, or both, can readily be increased or diminished to suit different riders, and by having the central space all along the saddle between the two upper portions $A' A^2$ of the same thorough ventilation of the seat is insured and any undue pressure on the rider's seat is obviated.

It will be evident that the construction of the curved back bar D and of the slides $C' C^2$ may be varied in many ways without departing from the nature of my invention. For instance, as shown by Figs. 5 and 6, the curved back bar D' may be made flat and the runners $C' C^2$ be bolted to the top side of the same by the bolts $f' f^2$, which pass through the slotted holes $d' d^2$ therein, and also pass through the eyes of the spring E ; or, as shown by Figs. 7 and 8, the runners $C' C^2$ may be clamped between the cross back bar D and another flat bar K , through all of which the bolts $f' f^2$ pass, the curved back bar D and top plate K being slotted to allow of the bolts being moved nearer together or farther apart when the width of the saddle is being adjusted; or the runners $C'' C^{20}$ may, as shown in Figs. 9 and 10, be made long enough to overlap and slide upon each other, so that the bolts $f' f^2$ will pass through both and enable the back bar D to be dispensed with.

The arrangement shown by Figs. 11, 12, 13, 14, and 15, in which the runners C''' are clamped by the bolts $f' f^2$ between the two plates K and D , is similar to that shown by Figs. 7 and 8, except that in the arrangement shown by Figs. 11, 12, 13, 14, and 15 the runners C''' are slotted for the bolts $f' f^2$ to pass through and the back plates K^{10} and D^{10} are strengthened by having ribs $k' d'$ raised upon them, respectively.

The two parts $A' A^2$ of the saddle may, if preferred, be connected together at the middle, as by the flexible cross-strips a' (shown in Figs. 2 and 4), or by other like means which will not interfere with the two parts $A' A^2$

being moved nearer together or farther apart, as above described.

What I claim as my invention, and desire to secure by Letters Patent, is—

1. In combination in a cycle-saddle, the two parts having sockets at their front ends, the cross-screw having right and left hand threads for adjusting the parts, the saddle-spring and the adjustable connection between the cross-screw and the front end of the spring whereby the cross-screw may be adjusted longitudinally of the saddle, substantially as described. 65

2. In combination, the two parts of the saddle, the saddle-spring, the cross-screw for adjusting the two parts of the saddle and the tension-screw J connecting the cross-screw with the spring said screw having its shank threaded into a portion of the cross-screw, substantially as described. 70

3. In combination in a saddle, the two parts, the runners secured to the back parts thereof and the saddle spring or springs with adjustable connections between the springs and the runners, said runners being slidable laterally to increase or decrease the width of the saddle at the rear, substantially as described. 75

4. In combination, in a cycle-saddle, the two top parts having the threaded sockets at their front ends with the right and left hand screw-threaded rod, the tension-screw connected therewith and with the springs, said screw being adapted for adjusting the tension and for adjusting the front ends of the two parts, and the adjustable slides or runners fixed to the rear ends of the two top parts with means for supporting the same adjustably, 80 substantially as described.

5. In combination with the two top parts of the saddle, the overlapping runners adapted to be adjusted one upon the other by sliding one part longitudinally upon the other 85 and the supporting spring or springs, substantially as described.

In witness whereof I have hereunto set my hand in presence of two witnesses.

JUAN EMILIO NOIRIT.
